UNITED STATES PATENT OFFICE.

GEORGE HEBARD PAINE, OF ROCKVILLE CENTER, NEW YORK.

DESIGN FOR A CONFECTIONERY OR CHEWING-GUM UNIT.

58,042.

Specification for Design.

Patented May 31, 1921.

Application filed May 17, 1920. Serial No. 382,184. Term of patent 14 years.

To all whom it may concern:

Be it known that I, GEORGE HEBARD PAINE, a citizen of the United States of America, residing at Rockville Center, county of Nassau, and State of New York, have invented a new, original, and ornamental Design for Confectionery or Chewing-Gum Units, of which the following is a specification, reference being had to the accompanying drawing, forming part thereof.

The figures of the drawing are perspec-

tive views of a confectionery or chewing gum unit showing my new design, Figure 1 showing three sides of the article and Fig. 2 showing the other three sides.

I claim:

The ornamental design for a confectionery or chewing gum unit as shown.

In testimony whereof I have signed this specification this 13th day of May, 1920.

GEORGE HEBARD PAINE.
